(57) **CLAIM**

The ornamental design for a fiber housing assembly, as shown and described.

DESCRIPTION

FIG. 1 is a top perspective view of fiber housing assembly showing our new design;

FIG. 2 is a left side view thereof;

FIG. 3 is a right side view thereof;

FIG. 4 is a top view thereof;

FIG. 5 is a bottom view thereof;

FIG. 6 is a front view thereof; and,

FIG. 7 is a rear view thereof.

The broken lines depicting the remainder of the fiber housing assembly show features that form no part of the claimed design.

1 Claim, 7 Drawing Sheets
